UNITED STATES PATENT OFFICE.

SAMUEL GREENEBAUM, OF KANSAS CITY, MISSOURI.

WALL BOARD.

Application filed January 21, 1928. Serial No. 248,410.

The invention relates to a new and improved wall board constituting a tile or analogous simulation, and it aims to provide an inexpensive, yet an effective tile representation which may be manufactured in rigid sheet form, may be readily sawed to size and shape, may be nailed in place against studs or the like and does not require a continuous wall or surface to which 5 it is secured, requires no cement to hold it in place, and embodies grooves bounding the tile simulations, said grooves being multifunctional, in that they constitute grooves in which to drive the attaching nails and 10 to secure it, requires no cement to hold it in place, and embodies grooves bounding the tile simulations, said grooves being multifunctional, in that they constitute grooves in which to drive the attaching nails and 15 grooves to later receive and retain a plastic pointing material, which material not only assists in giving the appearance of separate tiles and mortar between, but hides all nail heads and joints, the latter being always 20 made between simulations.

The invention may represent glazed or unglazed tile, ceramic tile, glazed or unglazed brick, mosaic, stone, marble, terra cotta, etc., and hence, even though such expressions as "tiles", "tile simulating areas" 25 or analogous expressions are herein used, it is to be understood that I am not restricted to the simulation of actual tiles.

With the foregoing in view, the invention 30 resides in the novel subject matter herein-after described and claimed, the description being accomplished by reference to the accompanying drawing.

Fig. 1 is a fragmentary elevation showing 35 a portion of the wall board nailed to studs.

Fig. 2 is a horizontal sectional view on line 2—2 of Fig. 1.

Fig. 3 is an enlarged horizontal sectional view on line 3—3 of Fig. 1.

Fig. 4 is a fragmentary elevation, the 40 grooves between the tile simulations having been filled with pointing material.

Fig. 5 is a detail horizontal sectional view on line 5—5 of Fig. 4.

In the drawing above briefly described, 45 the numeral 6 denotes an inherently rigid sheet which may be of any desired thickness, for instance from one-eighth to one-quarter of an inch, according to its composition and 50 consequent rigidity. Any desired material may be used for this sheet 6, but its structure is preferably homogeneous throughout its thickness and it is sufficiently stiff to permit nailing directly to studs or the like, without 55 requiring that a continuous flat surface be

provided to which to attach said sheet. Moreover, the sheet 6 is sufficiently rigid or stiff to prevent excessive weakening thereof by grooving its front face and hence it is not necessary that it be provided with any 60 backing of fabric or the like.

The front side of sheet 6 is formed with a plurality of grooves 7 arranged in any desired manner to bound tile simulating areas 8 of desired size and shape. After the formation of these grooves, the front side of the sheet is enameled, lacquered or finished in any other coating, as indicated at 9, to give the desired tile simulation.

In forming a tile representing wall, sheets 70 such as 6 may be cut to desired sizes and shapes with a saw or knife, always performing the cutting operation in a groove 7, if one sheet is to abut another sheet at the cut. The sheets are secured to studs S or to other 75 desired backing means, by small finishing nails 10 which are driven into the grooves 7, the heads of the nails being preferably driven against or partly into the groove bottoms by the use of a fine nail set. After 80 the sheets have been secured in place, the numerous grooves are filled with plastic pointing material 11, giving an excellent representation of individual tiles separately 85 applied and having mortar joints between them. Not only is this appearance given by application of the pointing material 11, but this material covers all nail heads and all 90 seams or joints between sheets so that it is impossible to detect where any joint was made.

It will be seen from the foregoing that 95 a new and improved tile simulating wall board has been provided which eliminates any fabric or other backing material on the sheets, requires no continuous surface such as a solid wall against which the sheets are to be secured, requires no cementing during the securing operation, may be manufactured easily and economically, and produces excellent results, all joints and nail heads being hidden from view by the plastic material 11 received in the grooves 7. These 100 grooves are of multifunctional nature, in that they not only receive the attaching nails 105 but later receive the pointing material 11 which obscures the nail heads and gives the desired appearance to the finished wall, not only forming distinct lines of demarcation 110 between the tile simulating areas of the

sheet, but breaking the mechanical monotony which would exist without the application of this pointing material.

As above stated, any desired material, appropriate for the purpose intended, may be used in the manufacture of the sheet 6. In practical experiments which I have made, I have found that waste wood material disintegrated under the action of steam and later hydraulically compressed into sheet form, will not only produce satisfactory results, but is rather inexpensive, and lends itself admirably to the operation or operations necessary in the formation of the grooves 7. In this connection, attention is invited to the facts that these grooves may be made by groove cutters where the tile design is simple, or in either simple or intricate designs or patterns, the grooving may be accomplished by stamping or indenting the sheet under pressure before hardening of the material of which it is formed takes place, and in some instances, the so-called stencilling process may be used in the formation of the grooves.

By the use of the invention, a facing of individual tiles and mortar may be so effectively simulated that it is practically impossible to distinguish the difference. In this connection, it may be explained that the grooves 7 are considerably deeper than the distance from the tile faces to the mortar of a conventional tile and motor facing. Hence, a substantial body of plastic point-

ing material 11 may be placed and retained in these grooves and the distance between this material and the faces of the tile simulations 8 may be made to agree exactly with the distance between the mortar and the tile faces of the conventional tile and mortar facing simulated. It is due to this and to skillful finishing of the tile simulating faces, that such excellent representations of conventional tile and mortar facings can be produced.

Obviously, any desired finishing material such as cap molding, base finishes, trim, etc., may be used with the wall board, constructed similarly to the article herein described.

I claim:—

Tile board for simulating a conventional facing of individual tiles laid with mortar joints, said board comprising an inherently rigid sheet penetrable to nails, the front side of said sheet being formed with nail and plastic-receiving grooves and tile-simulating areas bounded by said grooves, said grooves being of a depth considerably greater than the distance from the mortar joints to the tile faces of the conventional facing to be simulated, whereby said grooves may receive a substantial body of plastic pointing material to simulate the mortar and obscure the nail heads, said areas of said sheet each having a complete ornamental finish.

In testimony whereof I have hereunto affixed my signature.

SAMUEL GREENEBAUM.
